UNITED STATES PATENT OFFICE.

MARGARET H. STODDARD, OF BOSTON, MASSACHUSETTS.

SKIRT-HANGER.

1,262,280.

Specification of Letters Patent.

Patented Apr. 9, 1918.

Application filed April 28, 1916. Serial No. 94,264.

To all whom it may concern:

Be it known that I, MARGARET H. STODDARD, a citizen of the United States, residing at 18 Temple street, Boston, in the county 5 of Suffolk and State of Massachusetts, have invented certain Improvements in Skirt-Hangers, of which the following description, in connection with the accompanying drawings, is a specification, like reference 10 characters on the drawings indicating like parts in the several figures.

According to the usual practice of handling women's skirts in retail stores, each 15 skirt is suspended on a hanger, and the skirts, when not being shown, are kept in a case or compartment which is provided with a horizontal rod on which the hangers are supported in a row. These hangers usually consist merely of the ordinary garment 20 hanger provided with two hooks on the lower side of the hanger bar near its opposite ends, which serve to support the two loops with which a skirt ordinarily is provided. In showing these garments to a customer 25 the salesgirl must of course remove them from the case or compartment in which they are kept, and after the customer has made a selection, the other garments are returned to the case, usually by boys 30 who are employed simply to do this work. In the handling of these garments in this manner it is a very frequent occurrence for the skirt loops to slip off the hooks on which they are supported, thus allowing the 35 garment to fall on the floor. This frequently happens also while the garments are being put away in the cases or compartments in which they are kept, or are being handled incidentally to the selection or removal 40 of some other garment. They thus get trampled under foot in the rush of waiting on customers at very busy times; they become crumpled and their salability is greatly impaired. In fact the loss which is 45 sustained due to this cause by any department store or retailing establishment handling garments of this character, reaches very substantial proportions in the course of a year.

50 It is the chief object of the present invention to devise a skirt hanger that will overcome the difficulties just described, which can be economically manufactured, and which will fulfill the practical requirements 55 of an article of this character.

The manner in which it is proposed to ac-

complish these objects will be readily understood from the following description, reference being made to the figure of the accompanying drawing which shows, in side elevation, partly in section, a skirt hanger embodying the invention in the form now preferred.

The skirt hanger shown in the drawing comprises a hanger bar 2 of the usual shape, 65 equipped with a hook 4 by means of which it may be suspended in the usual manner. This hanger bar may be made of any suitable material, but in the form shown is made of wood, and is grooved on its lower 70 side near its opposite ends to receive two blocks 6 and 7, which are mounted to slide toward and from each other. The escutcheon plates 8 and 9 screwed to the lower face of the hanger bar retain the blocks 6 and 7 in 75 the grooves formed for them; and these plates are each slotted to permit the passage therethrough of the shanks of two hooks 10 and 11, which are supported, respectively, by the blocks 6 and 7. The blocks are 80 backed up by helical compression springs 12 and 13, respectively, which forces them 85 yieldingly away from each other and consequently tend to maintain the hooks 10 and 11 at their maximum distances apart. The 90 two loops L at the opposite sides of the skirt S are positioned respectively on the hooks 10 and 11, and the springs 12 and 13, acting in the manner just described, tend to keep the skirt loops taut at all times.

When these hangers with the skirts on them are picked up to return them to the cases, in the manner above described, they are likely to be tipped at various angles, since the boy doing this work usually has 95 several of these hangers in each hand. The tipping of the hangers in this manner, and the consequent shifting of the weight of the skirt from one loop to the other, causes these loops to slide around on the hooks on which 100 they are supported, and the hooks ordinarily used are so constructed that the loops can easily escape from them. In order to prevent this action I prefer to use a safety hook of some type. A great many constructions 105 of hooks obviously may be employed for this purpose, the requirement being that they shall be so constructed and arranged as to prevent the loop from accidentally slipping off the hook and shall not interfere 110 materially with the placing of the loops in the hooks or the removal of them from the

hooks when desired. In the construction shown, each hook has a V shape, one leg of the V being turned in so that its end lies very close to the other leg; and a small projection, indicated on the two hooks 10 and 11 at 14 and 15 respectively, is provided on the straight leg of each hook just below the end of the inturned leg. This projection is so positioned that it will deflect the loop, if it 10 slides up the straight leg, on to the inturned end portion of the bent leg and thus will prevent the loop from sliding out of the opening in the hook. Any other construction of hook, however, may be used that will 15 meet the requirements above indicated.

It is obvious that in using the construction above described the springs 12 and 13, by pressing the hooks 10 and 11 constantly away from each other, will tend to maintain 20 the skirt loops L so taut as to prevent the presence of enough slack to enable either loop to slip off its hook. Furthermore, by using a safety hook of some suitable construction all possibility of the loops escaping 25 accidentally from their hooks is substantially eliminated.

While I have described and shown the form of the invention now preferred by me, it is obvious that the invention may be embodied in other forms differing in details 30 from that shown, while still retaining its essential features and characteristics. I do not, therefore, desire to be limited to the precise details of the construction shown.

Having thus described my invention, what 35 I claim as new and desire to secure by Letters Patent of the United States is:

Copies of this patent may be obtained for five cents each, by addressing the "Commissioner of Patents, Washington, D. C."

1. A skirt hanger comprising a hanger bar, two hooks constructed to support the loops of a skirt and depending from said bar near its opposite ends, said hooks being mounted for sliding movement on the bar toward and from each other and being constructed to prevent the accidental movement of the loops of the skirt through the openings in the hooks, and springs within said bar acting on said hooks to force them yieldingly away from each other. 40 45

2. A skirt hanger comprising a hanger bar, two hooks constructed to support the loops of a skirt and supported by said bar near its opposite ends for movement toward and from each other, said hooks pointing away from each other and having means constructed to prevent the accidental movement of said loops through the openings in the hooks, and springs acting on said hooks to force them yieldingly away from each other. 50 55

3. A skirt hanger comprising a hanger bar, a pair of blocks mounted in said bar near its opposite ends for sliding movement toward and from each other, said bar being constructed to form a guideway for said blocks, two springs acting respectively on said blocks to force them yieldingly away from each other, and a hook carried by each block and constructed to support the loop of a skirt and to prevent the loop from escaping accidentally from the hook. 60 65 70

In testimony whereof I have signed my name to this specification.

MARGARET H. STODDARD.
